E. E. GREGORY,
NON-REFILLABLE BOTTLE,
APPLICATION FILED MAY 3, 1915.

1,172,982.

Patented Feb. 22, 1916.

Inventor
E. E. GREGORY

UNITED STATES PATENT OFFICE.

ELI E. GREGORY, OF CENTRAL CITY, KENTUCKY, ASSIGNOR OF ONE-HALF TO WILLIAM A. MACDONALD, OF CENTRAL CITY, KENTUCKY.

NON-REFILLABLE BOTTLE.

1,172,982.

Specification of Letters Patent. Patented Feb. 22, 1916.

Application filed May 3, 1915. Serial No. 25,546.

To all whom it may concern:

Be it known that I, ELI E. GREGORY, a citizen of the United States, residing at Central City, in the county of Muhlenberg and 5 State of Kentucky, have invented certain new and useful Improvements in Non-Refillable Bottles, of which the following is a specification, reference being had to the accompanying drawings.

10 This invention relates to non-refillable bottles and similar receptacles and has for its primary object to provide a bottle which cannot be fraudulently refilled without detection by the purchaser.

15 The invention has for an additional object to provide improved means for tightly sealing or closing the bottle, the neck portion of the bottle having an easily frangible section so that the same may be readily 20 broken off by the application of heat and access had to the seal or stopper whereby the contents of the bottle may be decanted.

It is an additional object of my invention 25 to produce a device of the above character which is simple and inexpensive in its construction and highly serviceable and reliable in practical use.

With the above and other objects in view as will become apparent as the description 30 proceeds, the invention consists in certain constructions, combinations and arrangements of the parts that I shall hereinafter fully describe and claim.

For a full understanding of the invention, reference is to be had to the following 35 description and accompanying drawings, in which—

Figure 1 is a side elevation of the upper portion of a bottle which is provided with 40 my invention; Fig. 2 is a vertical section; Fig. 3 is a detail perspective view showing the upper end of the bottle neck broken off and the stopper exposed; Fig. 4 is a section taken on the line 4—4 of Fig. 2; and Fig. 45 5 is a vertical section similar to Fig. 2, illustrating a slightly modified form of the invention.

Referring in detail to the drawing 5 designates the body of the bottle or other container and 6 the neck thereof. This bottle neck at a point intermediate of its ends is provided with a deep exterior annular

groove 7 and also with a relatively shallow interior annular groove 8 whereby a relatively thin wall section 9 is produced in the 55 bottle neck. At a point below the groove 8, the wall of the neck 6 is formed with an inwardly projecting annular enlargement 10 for a purpose to be later explained.

At the mouth of the bottle neck the same 60 is provided with an inwardly inclined or sloping end face 11 at the base of which the annular groove or seat 12 is formed. 13 designates the stopper which is formed of cork or other compressible material and is 65 of approximately the same diameter as the interior diameter of the bottle neck. This stopper is adapted to be forced into the neck of the bottle and beyond the inwardly projecting annular portion 10 of the wall thereof 70 of whereby the cork will be tightly compressed and extraction of the cork effectively prevented. The cork stopper 13 is provided with a central longitudinal opening or bore 75 to receive the stem 14 of a glass plug. Upon one end of the stem the circular head 15 is 80 formed having the concave outer face 16. It will be understood that the stopper and glass plug are first assembled and then inserted together into the neck of the bottle. The compressing action of the inward projection 10 on the bottle neck against the 85 cork stopper also creates a binding or tight frictional pressure of the cork body upon the glass stem 14 so as to securely hold the 90 plug in place within said stopper. As an additional means of security I provide a sheet metal disk 17 which is of slightly greater diameter than the interior diameter 95 of the bottle neck and is adapted to be forced into the mouth of the bottle upon the beveled or inclined wall 11 thereof. As said sheet metal disk is forced inwardly, it is gradually bent or curved until the edge of the disk is disposed opposite the annular seat or groove 12. Owing to the inherent resiliency of the sheet metal, the disk will attempt to assume its normal shape and the edge portions thereof will spring outwardly 100 into the groove or seat 12. The disk 17 will, however, still be slightly curved and will engage upon the concave face 16 of the head 15 on the glass plug. It will be observed that this head 15 on the plug is approxi-

mately equivalent in diameter to the interior diameter of the bottle neck and entirely covers the end of the cork stopper so that the stopper cannot be mutilated and particles thereof withdrawn by drilling through the sheet metal disk 17.

For the purpose of readily breaking the bottle neck at the reduced wall section 9 thereof, I preferably arrange in the exterior groove 7, a waxed taper indicated at 18. Assuming that the parts have been arranged in the manner shown in Fig. 2 of the drawing and the bottle tightly sealed after being filled, when the purchaser desires to decant the contents thereof, it is only necessary to ignite this waxed taper. The reduced section 9 of the bottle neck being thus highly heated, finally breaks. This break in the bottle neck will leave an even sharp edge on the lower section of the neck, and as the cork stopper 13 projects outwardly from the same it will be manifest that all possibility of chips or particles of the glass entering the interior of the bottle is precluded. The user now removes the glass plug from the cork stopper 13, so that the contents of the bottle may be poured out through the bore or opening in the stopper. In this manner, access to the contents of the bottle may be easily and quickly obtained as it is not necessary to remove the metal sealing disk 17, which part will of course be removed with the broken off end section of the bottle neck. The glass plug may be readily removed from the cork stopper by simply inserting a knife or other instrument between the head thereof and the end of the cork and then forcing or pulling out upon the plug. The cork stopper at all times remains in place and the bottle may be very securely sealed after use by reinserting the stem of the glass plug into the bore of the cork stopper.

In Fig. 5 of the drawing I have shown a slightly modified form of the device wherein in the bottle neck 6' is provided at some distance from its upper end or mouth with the downwardly tapering bore section 19 whereby an annular shoulder 20 is produced in the bottle neck. This shoulder may either be square or at right angles to the axis of the bottle neck or disposed at an inclination with respect thereto. In the periphery of the bottle neck and upon the exterior thereof and approximately in line with the point of juncture of the upper end of the tapering section 19 of the bore with the wall of the bottle neck, the annular groove 21 is formed therein to reduce or weaken said bottle neck. While in this form of the device I have illustrated only an exterior groove on the bottle neck, it will be understood that the same may be provided with an interior groove as well, as in the construction previously referred to. In this modified construction the mouth of the bottle neck is not

formed with the tapering or flared end wall 11, as the use of the metal sealing disk is eliminated and the compressing action upon the cork which causes the same to tightly bind and grip the stem of the glass stopper, 70 is alone relied upon to prevent the extraction of the stopper. The head 16' of the glass stopper is therefore not formed with the convex end face and is of such diameter as to fit tightly within the wall of the bottle 75 neck so as to prevent the insertion of an implement between the outer edge of said head and the neck wall. It will be apparent, that when the cork and the stopper are inserted into the bottle neck, the contracted 80 bore section 19 compresses the cork tightly upon the glass stem as the cork is pressed inwardly, said cork expanding under the shoulder 20 as clearly shown in the drawing. Thus the removal of the cork is effectively 85 prevented, and said cork stopper in turn operates by its gripping action upon the glass stem to prevent the removal of said stopper.

In lieu of providing an internal weakening groove in the neck of the bottle, the manufacturer may if desired, after the bottle is molded make a shallow cut in the inner surface of the bottle neck opposite to the exterior groove by means of a glass cutter. This cut need not be more than an eighth or 90 a quarter of an inch in length, which would be sufficient to insure the start of the fracture in the weakened portion of the bottle neck when the same is heated.

From the foregoing description taken in 100 connection with the accompanying drawing, the construction, manner of operation and certain advantages of my improved non-refillable bottle will be fully and clearly understood.

The several parts of the device being of exceedingly simple form, it is manifest that the invention as a whole can be produced at small manufacturing cost.

The invention provides a very effective 110 means for preventing the unauthorized refilling of bottles or other receptacles whereby purchasers might be deceived into the belief that the contents of the bottle is the product of the original manufacturer.

It is obvious that the invention may be manufactured in various sizes in accordance with the size cork of the bottle or receptacle to which it is applied.

The several parts may also be variously 120 modified in form and proportion and I therefore reserve the privilege of resorting to all such legitimate changes which may be fairly embodied within the spirit and scope of the invention as claimed.

What I claim is:

A bottle including a neck having its mouth inclined upon the inner face thereof and further provided with a circumferential groove at the base of the inclination, a 130

stopper insertible within the neck having a longitudinal bore, a plug engageable in the bore and provided with a concave upper face, and a pliable disk insertible within the mouth of the bottle, the edge of said pliable member contacting with the beveled face of the mouth as it is inserted therein, whereby the disk is caused to seat in the concave face

of the plug and its edge engaged in the circumferential groove.

In testimony whereof I hereunto affix my signature in the presence of two witnesses.

ELI E. GREGORY.

Witnesses:

JOHN WILKINS,
W. A. MACDONALD.
